Primary Examiner — Richard Kearney*Assistant Examiner* — Qiawen W Wiechert(57) CLAIM

The ornamental design for a TV stand as shown and described.

DESCRIPTION

FIG. 1 is a front, left and top perspective view of a TV stand showing my new design;

FIG. 2 is a front elevational view thereof;

FIG. 3 is a rear elevational view thereof;

FIG. 4 is a right view thereof;

FIG. 5 is a left view thereof;

FIG. 6 is a top plan view thereof;

FIG. 7 is a bottom plan view thereof;

FIG. 8 is a rear, right and bottom perspective view thereof; and,

FIG. 9 is an enlarged view of a portion labeled as 9 on FIG. 1.

The long dash-short dash broken lines depict enlargement boundaries that form no part of the claim. The evenly broken lines illustrate portions of the article that form no part of the claimed design.

1 Claim, 9 Drawing Sheets(56)
